UNITED STATES PATENT OFFICE.

CÁSTULO GONZÁLEZ, OF CROWLEY, COLORADO.

KEYLESS PADLOCK.

Application filed December 8, 1922. Serial No. 605,573.

To all whom it may concern:

Be it known that I, CÁSTULO GONZÁLEZ, a citizen of the Republic of Mexico, residing at Crowley, in the county of Crowley and 5 State of Colorado, have invented certain new and useful Improvements in Keyless Padlocks, of which the following is a specification.

This invention relates to padlocks, having 10 more particular reference to a type of padlock having concealed releasing means for the shackle, the invention having for an object the provision of a simple and inexpensive padlock of this type.

15 For further comprehension of the invention, and of the objects and advantages thereof, reference will be had to the following description and accompanying drawings, and to the appended claims in which the 20 various novel features of the invention are more particularly set forth.

Fig. 1 of the drawings is a face view showing one form of my improved padlock.

Fig. 2 is a like view with the face-plate 25 removed.

Fig. 3 is a horizontal sectional view taken on the line 3—3 of Fig. 2.

Referring first to Figs. 1 to 3 of the drawing the padlock comprises a main body 10 to which is secured a face-plate 11 by means 30 of screws 12, these screws being concealed by bosses 13 soldered on the face-plate. The shackle is shown at 14 and is here of U-shape with parallel legs which extend through 35 openings 15 cut in the body 10.

One of the legs of the shackle is formed 40 with a hook 16 adapted to be engaged by a hook 17 formed on top of a flat resilient strap 18 fixed at its lower end in the body 10. The other end of the shackle is formed with an enlarged head 19 accommodated in a recess 20 in the body 10 and pressed upward by an expansion spring 21 located in 45 said recess.

Extending through one side of the body 45 10, into the recess 22 which accommodates the member 18, is a plunger pin 23 whose outer end projects into a shallow concavity 24 formed in the side of the body 10. Extending around the sides and bottom of the 50 body 10 is a flat resilient strap 25 which extends across the concavity 24 at one end, this strap being suitably fixed to the said body 10.

By pressing inward on the portion of the 55 strap 25 which registers with the concavity 24 the pin 23 is forced inward and lifts the hook 17 on member 18 from the hooked end 16 of the shackle 14. The member 18 may be reinforced by a bow-spring 26 located in 60 the recess 22.

The strap 25 has the appearance of an 65 integral wall of the lock casing and since the pin 23 is completely concealed by the strap there is nothing which shows externally to reveal the manner of operating the lock.

Having thus described my invention what I claim as new and desire to protect by Letters Patent of the United States is as follows:

In a padlock, a body, a shackle, a resilient hooked member adapted to engage and lock one arm of the shackle, a spring in said body engaging the other arm of the shackle to 75 urge the latter outwardly, a pin slidable in said body and adapted to release said hooked member, and a resilient strap extending completely around the bottom and side edges of said body and covering the said pin, the 80 outer end of said pin being located in a recess in the side of the said body covered by the said strap.

In testimony whereof I have affixed my signature.

CÁSTULO GONZÁLEZ.
